(57) **CLAIM**

The ornamental design for a display screen with icon, as shown and described.

DESCRIPTION

FIG. 1 is a front view of a first embodiment of a display screen with icon showing our new design;

FIG. 2 is a front view of a second embodiment of a display screen with icon showing our new design;

FIG. 3 is a front view of a third embodiment of a display screen with icon showing our new design;

FIG. 4 is a front view of a fourth embodiment of a display screen with icon showing our new design;

FIG. 5 is a front view of a fifth embodiment of a display screen with icon showing our new design; and,

FIG. 6 is a front view of a sixth embodiment of a display screen with icon showing our new design.

(Continued)

The broken line showing the remainder of the display screen and the remainder of the device is for environmental purposes only and forms no part of the claimed design.

1 Claim, 6 Drawing Sheets
